Inventor.

UNITED STATES PATENT OFFICE.

FRANCIS M. RITES, DECEASED, LATE OF ITHACA, NEW YORK, BY CHARLES H. GALLAGHER, EXECUTOR, OF ITHACA, NEW YORK, ASSIGNOR TO PERIE CLAPP RITES, OF ITHACA, NEW YORK, GUARDIAN OF MARION B. RITES.

VALVE FOR INTERNAL-COMBUSTION ENGINES.

1,214,714.

Specification of Letters Patent.

Patented Feb. 6, 1917.

Original application filed January 17, 1913, Serial No. 742,720. Divided and this application filed May 27, 1915. Serial No. 30,852.

To all whom it may concern:

Be it known that FRANCIS M. RITES, deceased, late a citizen of the United States, residing at Ithaca and Slaterville Springs, 5 New York, in the county of Tompkins and State of New York, did invent certain new and useful Improvements in Valves for Internal-Combustion Engines, (described in his previous application, Serial No. 742,720, 10 filed January 17, 1913, of which this is a division,) of which the following is a specification.

The object of this invention is to produce a simplified form of valve mechanism for 15 an internal combustion engine.

Another object of the invention is to provide an improved device by which the combustion in an internal combustion engine is secured.

20 These and other objects of the invention will be fully illustrated in the drawings, described in the specification and pointed out in the claims at the end thereof.

This application is a division of prior 25 application No. 742,720, on which Patent 1,178,181 was issued April 4, 1916, to which reference is made for a more complete disclosure.

In the accompanying drawings, Figure 1. 30 shows a vertical section through the valve mechanism, the section being taken on the line 1^x—1^x of Fig. 2. Fig. 2 is a vertical section through the valve mechanism, the section being taken on the line 2^x—2^x of Fig. 1. Fig. 3 is a vertical section taken 35 through the baffle plate and cylinder head, the section being taken on the line 3^x—3^x of Fig. 2. Fig. 4 is a horizontal section through the valve chamber, the section being taken on the line 4^x—4^x of Fig. 2.

In the accompanying drawings like reference numerals indicate like parts.

In the drawings reference numeral 1 indicates a cylinder of an engine on which is 45 fastened a cylinder head 2. In this cylinder head is a valve chamber at the bottom of which is located a baffle plate 3 having an opening 4 extending therethrough. A nozzle 5 is placed at one end of this opening 50 having an air supply tube 6 and an oil supply tube 7 communicating therewith. The air supply tube 6 connects with the tube 8

through which air under pressure is furnished to the valve chamber for use in the engine. Through the nozzle 5 a mixture of 55 oil and air is blown through the tube 4 and is burned therein for the purpose of heating the baffle plate through which the opening goes. The opening 4 is enlarged at 20 for the purpose of increasing the combustion space and to reduce the thickness of 60 the baffle walls causing the outside of the baffle, where it is exposed in the valve chamber, to heat quicker from the combustion within. The products of combustion from 65 the nozzle 5 pass through the tube 4 and into the outer air. Centrally on this baffle plate is formed a valve seat 9. Concentric with the seat 9 a flange 10 is formed in the valve chamber and on this flange is formed 70 a valve seat 11, the seat 11 being concentric with the seat 9. The seats 9 and 11 may be referred to as two concentric tapering surfaces of a single valve seat. Coöperating with the valve seats 9 and 11 is a valve 12-75 which has a central opening 13 therein with which opening communicates the oil supply tube 14, the valve being formed with an upwardly extending tube 15 which surrounds the stationary tube 14 and makes a tight 80 sliding connection therewith. The tube 14 is stationary and the valve 12 is free to rise and fall so as to control the feed of oil from the tube 14 to the baffle 3.

For the purpose of lifting the valve a 85 rocker arm 16 is provided, pivoted at 17 and operated by a link 18, which link is driven from a rock shaft of the engine in the usual manner.

As the valve 12 rises it lifts from both the 90 seat 9 and the seat 11. Oil is admitted past the seat 9 and compressed air is admitted past the seat 11. The air and oil come into contact with each other and into contact with the baffle plate 3 which is maintained 95 at an igniting temperature, first by the torch or nozzle 5 and afterward as a result of the combustion. This causes the oil to burn with the air which burning is continued through a definite interval of time 100 rather than during merely an instant which would characterize an explosion as ordinarily occurs in a combustion engine in which the charge is mixed and compressed

before it is ignited. While in this engine, with which this valve mechanism will be used, the combustion will begin as soon as the valve lifts to admit the air and oil to the baffle plate and will continue until the valve closes again. The valve will not lift until the forward stroke of the piston is about to begin and the valve will remain open for a considerable fraction of the piston stroke. That is, through one sixth or a third or even one half or more of the 180° of the piston stroke.

To secure the admission of oil past the valve seat 9 the oil in the tube 14 is kept under sufficient pressure to cause the oil to feed against the resistance of the compressed air which is fed past the valve seat 11. As the compressed air and oil burn the volume of it increases. The pressure of it does not increase. If it did the air would be pushed back through the tube 8, cutting off further combustion. Instead, however, the piston of the engine is pressed down and the products of combustion advance from the baffle through the openings 21 and as they advance from the baffle they expand into the engine cylinder, causing the engine to generate power. As they advance they make room for the air and oil that passes the valve 12 to support the combustion which continues as long as the valve remains open. To insure proper feed the parts will be proportioned so that the pressure in the engine cylinder is slightly less than the pressure in the air pipe 8.

Claim:

1. In a valve mechanism for an internal combustion engine the combination of a chamber, a stationary valve seat therein having two stationary concentric tapering surfaces thereon with an annular opening between them, a valve in said chamber engaging therewith and having two concentric tapering surfaces thereon to engage with the surfaces of the seat, a passage in the chamber for conveying one element of combustion to one surface of the valve seat, a stem on said valve, a passage through said stem for conveying another element of combustion to the other surface of said valve seat.
2. In a valve mechanism for an internal combustion engine the combination of a chamber, a valve seat therein having two concentric tapering surfaces thereon with an annular opening between them, a valve in said chamber engaging therewith and having two concentric tapering surfaces thereon to engage with the surfaces of the seat, said valve having a perforated stem through which it is adapted to pass one element of combustion into the opening, the other element of combustion surrounding the valve stem and passing along the outside of said valve into said opening, means for heating said valve seat from outside of the engine to

promote the combustion of the elements admitted by said valve.

3. In a valve mechanism for an internal combustion engine the combination of a chamber, a valve seat therein having two concentric tapering surfaces thereon with an annular opening between them, a valve in said chamber engaging therewith and having two concentric tapering surfaces thereon to engage with the surfaces of the seat, said valve having a perforated stem through which it is adapted to pass one element of combustion into the opening, the other element of combustion surrounding the valve stem and passing along the outside of said valve into said opening, said valve seat having an opening therethrough sealed from the chamber and communicating with the outside air through which said valve seat may be heated to cause the heating and burning of the combustible elements as they pass into the cylinder.

4. In a valve mechanism for an internal combustion engine, the combination of a chamber, a valve seat therein having two concentric tapering surfaces thereon extending between two parallel horizontal planes and sloping toward each other with an annular opening between them, a mixing valve in said chamber engaging therewith and having two concentric tapering surfaces thereon to engage with the surfaces on the seat, means for introducing a separate fluid to each concentric surface, said fluids mixing in the annular opening when the valve lifts.

5. In a valve mechanism for an internal combustion engine, the combination of a chamber, a valve seat therein having two concentric tapering surfaces thereon extending between two parallel horizontal planes and sloping toward each other with an annular opening between them, a mixing valve in said chamber engaging therewith and having two concentric tapering surfaces thereon to engage with the surfaces on the seat, said valve having a perforated stem through which it is adapted to pass one element of combustion into the opening, the other element of combustion surrounding the valve stem and passing along the outside of said valve into said opening.

6. In a valve mechanism for an internal combustion engine the combination of a chamber, a mixing valve mounted to operate therein, said valve comprising a stationary female seat, having a stationary male seat concentric thereto, said seats tapering toward each other and extending between two parallel horizontal planes with an annular opening between said seats, a movable valve stem having corresponding seats thereon adapted to seat themselves on said stationary seats at the same instant to close said valves, means for introducing a separate fluid to

each concentric surface, said fluids mixing in the annular opening when the valve lifts.

7. In a valve mechanism for an internal combustion engine the combination of a 5 chamber, a stationary valve seat therein having two stationary concentric tapering surfaces thereon with an annular opening between them, a valve in said chamber engaging therewith and having two concentric 10 tapering surfaces thereon to engage with the surfaces on said seat, the passages controlled

by said valves each discharging directly into said annular opening between the seats.

In testimony whereof I affix my signature in presence of two witnesses.
